FIG. 1

FIG. 2

INVENTOR.
William A. Yonick

BY William J. Jackson.
ATTORNEY.

UNITED STATES PATENT OFFICE.

WILLIAM A. YONICK, OF PHILADELPHIA, PENNSYLVANIA.

HOUSEHOLD ARTICLE.

1,330,107.

Specification of Letters Patent.

Patented Feb. 10, 1920.

Application filed May 15, 1919. Serial No. 297,423.

To all whom it may concern:

Be it known that I, WILLIAM A. YONICK, a citizen of the United States, residing at the city of Philadelphia, county of Philadelphia, and State of Pennsylvania, have invented a certain new and useful Improved Household Article, of which the following is a specification.

The principal object of the present invention is to provide an improved household article designed for readily removing metallic tops from glasses such as contain jelly, mustard, peanut butter and similar commodities.

15 The invention consists of the improvements hereinafter described and finally claimed.

The nature, characteristic features and scope of the invention will be more fully understood from the following description taken in connection with the accompanying drawings forming part hereof, and in which:

25 Figure 1, is a view in elevation of the improved household article and illustrating the same in position for the removal of a metallic top from a glass, and

Fig. 2, is a view of the underside of the household article.

30 For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

40 In the drawings 10 designates an elongated member of thin metal, conversely curved arch-fashion throughout the major portion of its extent. One end of said member is provided with a handle 11 preferably of wood. The opposite end thereof is provided with a claw 12 extended in a direction toward said handle, which claw has a knife-like edge for engaging under the rim of a metallic top 13 of a glass 14. In removing

such a top, that part of the member 10 adjacent the handle 11 is positioned upon the peripheral edge of the top 13 to form a fulcrum. By exerting pressure upon the handle 11 in a downward direction the rim of the top is sprung free of engagement with a glass. The above described article provides an excellent kitchen adjunct and when so desired may be used exclusively for the purpose above stated. In such case the member 10 and claw 12 may be formed in one piece. However the member 10 may be provided with other devices to form a combination article. In such case the claw 12 may be manufactured as illustrated in the drawings wherein 15 designates a bifurcated part rigidly attached, as by a rivet, to the end of member 10. Such part 15 terminates at one end in the claw 12 and at its other end in a tooth 16 for prying loose the lids of tin cans such as are usually employed for containing syrups, paints and the like.

It will now be apparent that I have devised a novel and useful construction which embodies the features of advantages enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. An article of the character stated comprising a thin, flat one-piece member which is arched throughout the major portion of its extent, a bifurcated part fitted over one end of said member and rigidly fixed thereto, said part having formed integral therewith a claw having a knife-edge and a handle rigidly fixed to the other end of said arched member, that part of said member adjacent said handle serving as a fulcrum for the operation of said claw.

2. An article of the character stated comprising a thin flat one-piece member disposed edgewise which is arched throughout

the major portion of its extent, a thin substantially flat claw fixed to one end of said member said claw having a broad plane upper surface and the under surface thereof being tapered toward said upper surface to provide a knife-edge at the inner end of said claw, an end of said member abutting

against the upper face of said claw and a handle secured to the opposite end of said member.

10

In testimony whereof, I have hereunto signed my name.

WILLIAM A. YONICK.
